AUGUSTE ANTOINE, OF LE CHILLOT, FRANCE.

LAY-ACTUATED BOBBIN-CHANGING DEVICE.

Application filed March 28, 1923, Serial No. 628,279; and in France May 4, 1922.

The subject of the present invention is an automatic and rational device for changing the weft for mechanical weaving looms, enabling these latter to maintain their normal maximum speed.

This device is of the type called "oscillating with vertical charging" and is characterized by the feature that the magazine of tubes or cops and the loader form one oscillating whole, coming into contact above the shuttle box on the lay, at the start of the stroke of this latter, from back to front, and accompanying it until the end of the stroke, whilst the change is effected from above downwards, during the whole stroke of the beater.

This vertical change is therefore progressive and very gentle, and it is effected during the time of the traverse of the lay from back to front, thus permitting the looms to maintain their normal maximum speed.

This device for changing the weft, the subject of the present invention, is herein-after described in its principle of working and is represented diagrammatically by way of example of realization, in the drawings annexed to the present descriptive memorandum, in which:

Fig. 1 is a general view giving a side elevation.

Fig. 2 is a view giving a side elevation of a modification of the device for actuating the cop magazine oscillating with vertical loading.

Fig. 3 is a front view of same, and Fig. 4 a plan seen from above.

According to Fig. 1, such a device, applicable to all kinds of mechanical looms, with horizontal or vertical picking motion, comprises a support 1, fixed behind the breast-beam 2, on the side opposite the weft-stop motion mechanism or of the weft feeler, this support being appropriate to the kind of loom.

At the upper part of support 1, is articulated on the spindle 3 a vertical lever 4 having a small oblique arm 5 with a finger 6 solidly fixed to it, the finger 6 bearing against the large obliquely disposed lever 7 also articulated on the same spindle 3.

The lower end of the large vertical lever 4 has articulated on it a horizontal lever 8, the angular displacement of which above 8, the horizontal is prevented by a stop 9, rigidly fixed to the lever 4, or otherwise ar-

ranged, and the angular displacement of which below the horizontal is effected by a finger 10, fixed to the end of another horizontal lever 11, keyed on to a shaft 12, running the length of the breast-beam 2 and on the opposite end of which is keyed a vertical lever 13 which is engaged by and pushed forward by the hook of the weft fork, when the latter, on the occasion of the breaking of a weft thread is itself pushed back towards the front by the hammer.

When, owing to the oscillation of this vertical lever 13, bringing about the partial rotation of shaft 12, the lever 11 is lifted, its finger 10 effects the lifting of the lever 8 to the horizontal position which, being thus placed, comes opposite the lay 14 on the occasion of its forward stroke, and is pushed back during its traverse towards the breast-beam 2, resulting in the oscillation of the vertical lever 4 and the lowering of the small arm 5, the finger 6 of which bears upon the lever 7 and carries it along towards the vertical position.

At the upper part of the support 1 in front of the spindle 3, is articulated on a spindle 15, the cop or bobbin-carrying magazine 16 suspended so as to oscillate. This magazine comprises, as usual, a passage 17 for the heads of the cop spindles and a supporting plate for the bodies of the cops 18, 18^a, 18^b, etc., introduced one after another into the upper part of the magazine from an interchangeable reserve 19 and expelled at the lower part of the magazine where the cop or bobbin 18, ready to be loaded into the shuttle 20, is held by two springs 21.

The oscillation of the magazine 16 is actuated by the loader which comprises a pusher 22, sliding in guides fitted alongside the passage 17, and forming a slide 23, which pushes the last bobbin 18 from above downwards, to the end of the passage 17 of the magazine 16 this pusher being mounted on a spindle 24, fixed at the end of the oscillating lever 7 set in motion by the finger 6.

By this arrangement, the magazine 16 and the loader or pusher 22 constitute an oscillating whole around the spindle 15, actuated by the oscillation of the lever 7 around the spindle 3, the distance between these two spindles 15 and 3 controlling the displacement of the pusher 22 in its slide channel 23, the action of which, dependent upon the oscillation of the lever 4 under the

thrust of the lay 14 acting on the lever 8, is supported by the action of the lay 14, which from the commencement of its stroke forwards and after having commenced to 5 push against the horizontal lever 8, which has caused a slight oscillation of the magazine 16, comes into contact by its shuttle box 25, with the lower part of the said magazine 16, which it carries along with it 10 up to the end of the stroke, and leaves, after the change is effected, at the time of its return backwards; the exhausted weft cop being ejected outside of the shuttle 20, downwards through the groove 26.

15 Thus constituted, the working of this device of automatic change of bobbin is as follows:

So long as the weft is not broken or the 20 cop still contains enough thread, the levers actuated by the weft-stop motion or by the feeler, remain in the position indicated in dotted lines, and the beater 14, at the time of its forward blow, not coming up against the horizontal lever 8, does not cause any 25 displacement of the magazine 16 nor of the loader 7—22.

When, the beater being at the end of its stroke, at the back, as shown approximately in dotted lines, and when, through the weft-stop motion, for example, the levers have been brought into the position indicated in full lines, in consequence of the breaking of the weft, it happens that, towards the commencement of its forward stroke, the 30 said beater 14, coming against the lever 8, pushes it back, which causes the oscillation of the lever 4 in the direction of the arrow, hence the oscillation of the lever 7, under the action of the finger 6, and the descent 35 of the pusher 22, which causes the oscillation of the magazine 16 in the direction of the arrow.

By the beginning of this oscillation which corresponds to the start of the thrust of 45 lever 8 by the beater 14, the end of the magazine comes into the path of the box 25 of the beater, which pushes it back at the same time as the lever 8, which is displaced, during the whole of the forward stroke of 50 the beater, by the descent of the pusher 22, resulting in the passage of the bobbin 18 into the shuttle 20 and the expulsion of the empty bobbin through the slot 26.

From the start of its backward stroke, 55 the lay leaves the lever 8, as well as the end of magazine 16, which, with all its parts carried along with it, is brought back into its normal position by one or more springs 60 27, suitably fitted for the purpose.

The actuating of the magazine and of the loader can also be effected under the action of the weft-breaker or of the feeler solely by the direct action of the beater, giving 65 thus full security whilst avoiding false operation.

For this purpose the oscillating lever 7 of the loader 22, remains mounted on its pivot 3, but it is arranged on the other side of the bobbin-carrying magazine 16 and is not actuated by any device, the levers 5, 70 4, 8 and 11 being dispensed with and replaced by the following actuating mechanism for the magazine and loader as represented in Figures 2, 3 and 4.

On the spindle 15 which carries the oscillating magazine 16, and mounted on the side opposite the lever 7 of the loader 22, there is a lever 28, oscillating freely, which ends at the height of the lower end of the magazine by a projection 29, which is preferably 75 of triangular section.

The lever 28 is attached to the magazine 16 by a stirrup like device or collar 30, which partially surrounds the said magazine, leaving it however a suitable amount 80 of play 31.

Attached to lever 28, and oscillating about the spindle 15, is a small lever 32, on which bears a strong blade spring 33, mounted on a small lever 34, keyed on the end of 90 the rod 12 of the weft-stop motion and at the opposite end of the lever 13 which, when actuated by said weft-stop motion brings about the partial rotation in the direction of the arrow.

On the lay, at the entrance of the shuttlebox in which the change takes place, there is fixed an incline 35 of suitable form, in which there is a slot 36, the whole being arranged in the vertical plane of the finger 29 from which it is at a small distance when the loom is working normally and when the magazine is in an inoperative position, being drawn back by its springs 27.

Thus constituted and simplified, this device for actuating the magazine and the loader, works as follows:

When the weft-breaker or the feeler is working, acting on the lever 13, the spindle 12 makes the spring 33 oscillate in the direction of the arrow and with it the small arm 32 fixed to the lever 28 thus causing the latter to oscillate. On account of the play 31, left between the stirrup 30 and the magazine 16, the stirrup comes into contact with the magazine and carries it along during the movement of oscillation of the lever 28, at the same time as the projection 29, lowered from the commencement of the oscillation of the lever 28, is caught in the passage of the lay by the angle of the incline 35, which engages it during the advancement of the beater and directs it into the slide 36, which carries the lever 28 and the magazine, and consequently compels the loader 22 to slide towards the bottom of the magazine, pushing down the fresh cop into the shuttle 20.

As soon as the lay returns, the projection 29 is released from its slide 36, and the 130

magazine as a whole, is carried back into the normal position by the spring or springs 27 arranged for the purpose.

In this actuating device, the action of 5 the weft-stop motion or of the feeler starts, the oscillation of the lever 28, just sufficiently to engage the projection 29 with the passage of the incline 35, the oscillation of the magazine being thereupon 10 actuated by the forward stroke of the lay.

This system serves at the same time as a simple and solid safety mechanism which cannot get out of order. If the apparatus 15 should not, for any reason, return into its normal position, the loading takes place, a suitable mechanism however throwing the loom out of gear after three consecutive changes.

When the reserve 19 is exhausted, it can 20 be replaced by another, filled with cops which pass at each oscillation of the magazine into the slide 17 from whence they descend successively to the opening from which they are expelled by the pusher 22 25 into the shuttle 20, the opening of which is juxtaposed to that of the magazine during the whole of the course of the forward stroke of the beater.

It is understood that this device may 30 have modifications, changes and improvements in the details, and in the construction of the parts constituting it, without departing from the spirit of the invention.

What I claim is:

35 1. In a loom, a lay, mechanism operative upon a failure of weft, a magazine for cops normally stationary but yieldingly movable into the path of the lay where it will be engaged and operated by the lay 40 during its forward movement, means rendered effective by said mechanism upon a failure of weft for shifting the magazine into the path of the lay, and charging means associated with the magazine and operated 45 by the forward movement thereof for ejecting a cop from the magazine and inserting it into the shuttle box during the forward travel of the magazine and lay.

2. In a loom, a lay, a magazine hinged 50 for movement into the path of the lay so as to be engaged and moved forwardly by the latter during the latter part of its forward travel, means yieldingly holding the magazine out of the path of the lay, a 55 charger provided upon the magazine and operative to eject a cop from the magazine and insert it in the shuttle box, an arm hinged eccentrically of the magazine pivot and connected to the charger whereby swinging 60 of the magazine will cause an operation of the charger, and means operative upon said magazine through said arm for shifting the magazine into the path of the lay for operation thereby upon a failure of 65 weft.

3. In a loom, a lay, a magazine hinged upon a fixed point of the machine for movement into and out of the path of travel of the free end of the lay, so as to be engaged and operated thereby, a charger device 70 carried by the magazine for ejecting a cop from the magazine and inserting it into the shuttle box of the lay, and means acting between the charger device and a fixed point eccentrically of the magazine 75 hinge for causing rotation of said charger about said fixed point and thereby operating the charger by the mere movement of the magazine.

4. In a loom, a lay, a magazine hinged 80 upon a fixed point of the machine for movement into and out of the path of travel of the free end of the lay, so as to be engaged and operated thereby, a charger device 85 carried by the magazine for ejecting a cop from the magazine and inserting it into the shuttle box of the lay, an arm hinged to a point eccentrically of the magazine pivot and connected to the charger to operate the latter upon a movement of the magazine, means movable into and out of the path of the lay and which when operated by the lay will shift said arm to move the magazine into the path of the lay to be operated directly therefrom, and means operative 90 upon a failure of weft for moving said lay operated means into the path of the lay for operation therefrom.

5. In a loom, a lay, a cop magazine hinged 100 upon a relatively fixed point of the machine for movement into the path of travel of the free end of the lay so as to be operated directly therefrom, means for moving the magazine into the path of the lay and having a portion shiftable into the path of the lay for operation therefrom, means operative upon a failure of weft for shifting the first means into the path of the lay, and a charger device on the magazine 105 operative by the movement of the magazine 110 to eject a cop from said magazine and insert it into the shuttle box on the lay.

6. In a loom, a lay, a cop magazine hingedly suspended above the lay for swinging movement forwardly and rearwardly, means for holding the magazine out of the path of the upper end of the lay, the lower end of the magazine having a discharge exit which, when the magazine is engaged and pushed forwardly by the lay will move along with and over the shuttle box on the lay as the lay approaches its forward limit of travel, means operative upon a failure of weft for shifting the magazine into the path of the lay to be engaged and operated thereby, said last named means having a portion shiftable into the path of the lay for operation therefrom, and charger means on the magazine operated automatically by 120 the forward movement of the magazine for 125 130

ejecting a cop from the magazine and into the shuttle box.

7. In a loom, a lay, a cop magazine mounted so as to move into the path of the free edge of the lay and move therewith during the latter part of its forward travel, said magazine having a discharge opening which moves in approximate alignment with the shuttle box of the relay during said latter part of the lay travel, and charging means associated with the magazine and operated directly by the forward movement of the magazine for ejecting a cop from the magazine and inserting it into the shuttle box

8. In a loom, a lay, a cop magazine mounted so as to move into the path of the free edge of the lay and move therewith during the latter part of its forward travel, said magazine having a discharge opening which moves in approximate alignment with the shuttle box of the lay during said latter part of the lay travel, a charger device slidable on said magazine for ejecting a cop from the magazine and inserting it into the shuttle box, and a link articulately connected at one end to said charger device and at its other end anchored to a relatively fixed point at one side of the magazine.

9. In a loom, a lay, a cop magazine mounted so as to move into the path of the free edge of the lay and move therewith during the latter part of its forward travel, said magazine having a discharge opening which moves in approximate alignment with the shuttle box of the lay during said latter part of the lay travel, a charger device slidable on said magazine for ejecting a

cop from the magazine and inserting it into the shuttle box, a link articulately connected at one end to said charger device and at its other end anchored to a relatively fixed point at one side of the magazine and means operative automatically upon a failure of weft for causing a movement of the magazine into the path of the lay.

10. In a loom, a lay, a magazine hinged in proximity to the lay, and means associated with the lay and magazine for effecting the transfer of a cop from the magazine to a shuttle box upon the lay automatically upon a failure of weft, said means including a charger movably mounted on the magazine, and means connected between the charger and an anchorage point relatively stationary with respect to the hinged movement of the magazine so that the charger will be automatically operated by the movement of the magazine.

11. In a loom, a swinging lay, a cop magazine hingedly suspended above the lay to permit of swinging movement through a sector intersecting the sector of movement of the lay, means for normally holding the magazine out of the path of the lay, means operative upon a failure of weft for swinging the magazine into the path of the lay to be engaged thereby, and charger means on the magazine and operated directly by the swinging movement of the magazine for ejecting a cop from the magazine and inserting it into the shuttle box of the lay.

In witness whereof, I hereunto subscribe my signature.

AUGUSTE ANTOINE.
